(57) **CLAIM**

The ornamental design for a flexible energy transfer system, as shown and described.

DESCRIPTION

FIG. 1 is a perspective front view of a flexible energy transfer system;

FIG. 2 is a front elevation view of the flexible energy transfer system;

FIG. 3 is a rear elevation view of the flexible energy transfer system;

FIG. 4 is a left elevation view of the flexible energy transfer system;

FIG. 5 is a right elevation view of the flexible energy transfer system;

FIG. 6 is a top plan view of the flexible energy transfer system;

FIG. 7 is a bottom plan view of the flexible energy transfer system; and,

FIG. 8 is a perspective exploded view of the flexible energy transfer system.
